TIMER

Filed May 7, 1925

INVENTOR.

BY *Charles Knapp,
Attala, Jones
ATTORNEY.*

UNITED STATES PATENT OFFICE.

CHARLES KNAPP, OF SHERMAN, TEXAS.

TIMER.

Application filed May 7, 1925. Serial No. 28,681.

This invention relates to timers and particularly to rotary timers of the type commonly employed in connection with the ignition systems of Ford automobiles.

5 The general object of the invention is to provide a construction of timer in which the contact roller carrier bracket is mounted on its supporting bracket close to the timer shaft, leaving a clear field for the carrier bracket swing and for the annular travel of the roller and avoiding all liability of the roller and carrier bracket coming in engagement with two contacts at one time, and causing short circuiting and grounding of 10 the current and burning of parts, and also to provide a novel construction and arrangement of the pressure spring whereby even and positive pressure of the contact points is ensured and excessive vibration and ham- 15 mering of the roller on the raceway and resultant pitting of the raceway prevented.

20 A further object of the invention is to provide a novel construction of supporting and roller carrier brackets and mode of connecting the same and mounting the pressure spring whereby a rotor construction is produced which is adapted to be manufactured and sold at a comparatively low cost.

25 The invention consists of the features of construction, combination and arrangement of parts, hereinafter fully described and claimed, reference being had to the accompanying drawing, in which:—

30 Figure 1 is a sectional elevation of my improved timer taken on line *x*—*x* of Figure 2.

35 Figure 2 is a section taken on line *y*—*y* of Figure 1.

Figure 3 is a perspective view of the supporting bracket.

40 Figure 4 is a perspective view of the roller carrying bracket.

Figure 5 is a perspective view of the pressure spring.

45 Figure 6 is a view of the blank from which the supporting bracket is made.

Figure 7 is a view of the blank from which the roller carrying bracket is made.

50 Referring now more particularly to the drawing, 1 designates the timer casing, provided upon its interior with a ring 2 of insulating material, the inner surface of which forms an annular raceway, in which raceway are embedded the contacts 3 associated with the binding posts 4 to which the conductor terminals 5 are attached. The raceway, of which the contacts 3 form a part,

is arranged concentric with the timer shaft 6, carrying the contact rotor constructed in accordance with my invention.

55 The contact rotor comprises two members, to wit, a supporting bracket member 7 and a roller carrying bracket member 8. The member 7 is formed from the blank shown in Figure 6, the corresponding portions of the completed blank and member being des- 60 ignated by the same reference characters.

As shown, the bracket 7 comprises a sleeve portion 9, formed by rolling the body portion of the blank into cylindrical form, said sleeve portion being provided at one end 65 with a pair of short arms 10 and an intervening recess 11 and at its opposite end with a single central arm 12 bifurcated at its outer portion to form limbs 13 coiled to produce spaced eyes in the completed bracket. 70

Shoulders 14 are formed at the opposite side of the body of the bracket at its point of juncture with the arm 12. In shaping the blank, which may be stamped out from sheet material of proper kind and thickness, the 75 arm 12 is brought to engage the recess 11 and lie between the arms 10 with said arms 10 abutting against the shoulders 14, the arm 12 projecting beyond the periphery of the sleeve 9 at a tangent thereto. By this 80

construction the ends of the blank forming the sleeve are readily shaped and interlocked without additional fastening means, and the arm 12 and its eyes 13, which support the contact roller bracket 6, are reinforced by 85

the interlocking connection so as to effectually withstand all the working strains falling thereon. The sleeve 9 is fitted upon the shaft 6 and provided with a notch 15 to receive a locking pin or key 16, whereby it 90 is held from longitudinal displacement and from rotary motion thereon. As shown in the present instance, the pin or key 16 is held in position by a flanged washer 17 and nut 18 applied to the shaft. Formed in the 100 sleeve 9 is an opening 19, the walls of which are suitably beveled, the purpose of which opening is hereinafter described.

105 The roller carrier bracket 8 also consists of a stamping made from the blank shown in Figure 7. This bracket comprises a pair of parallel side plates 20 having registering openings 21 and 22 at their opposite ends, the outer longitudinal edges of said plates 20 being joined by a transverse bridge piece 110 23, the body portion of the bracket, constructed as above described, being substan-

tially of H-shaped formation. The rear edge of the bridge piece 23 has extended therefrom a segmentally curved tongue 24 extending on an arc of curvature concentric with the openings 21. The openings 21, which form eyes at the rear ends of the plates 20, are arranged upon the outer sides of and in alinement with the eyes of the bracket 7, through which openings and eyes 5 are passed a pin or shaft 25 pivotally coupling the rear end of the carrier bracket 8 to the tangential arm 12 of the supporting bracket 7, whereby said bracket 8 is properly mounted for rotation with the shaft 6 10 and for pivotal movement between the shaft and the surface of the raceway. A contact roller 26, of good conducting material, is disposed between the forward ends of the plates 20 and journaled for rotation upon a pin or shaft 27 received in the openings or eyes 22. The periphery of this roller runs in contact with the raceway and periodically engages the contacts 3, as will be readily understood. A coiled spring 28 encircles 15 the pivot pin or shaft 25 between the eyes 13, and one end of this spring is arranged to bear upon and exert pressure against the underside of the bridge piece 23, while the other end of said spring is hooked over the outer edge of the arm 12 between the eyes 13, said spring thus operating to resist inward pivotal movement of the bracket 8 and roller 26 and to yieldingly force said bracket and roller outward to 20 maintain the roller in contact with the surface of the raceway. The described construction of the brackets and mode of mounting the spring, provides a housing for the body portion of the spring and its compact arrangement, so that a spring of very small size may be employed. The rear portion of this spring is surrounded by the tongue 24 which acts as a guard to prevent passage of foreign substances to the spring coil and causing clogging thereof, and the free end of this tongue serves as a stop to engage the arm 12 and thereby limit the outward movement and bearing pressure of the roller 26 25 on the surface of the raceway.

50 The operation of the device will be readily understood by those versed in the art without further description. It is to be observed, however, that the rotor construction described enables the bracket members thereof to be stamped out and assembled in a ready and convenient manner, thus ensuring economy of manufacture, and it will further be seen that the structural formation of the brackets ensures their rigidity and freedom from tendency to breakage under working strains. By extending the arm 12 tangentially to the sleeve, this arm may be made very short, with the result that the pivoted end of the contact carrier bracket 8 55 will lie close to the sleeve and shaft, giving

a free range of movement in the raceway channel to the free end of the carrier bracket and the contact roller and ensuring only that the roller itself will engage the contacts 3, thus avoiding any possibility of the bracket itself engaging a contact and with the roller bridging adjacent contacts and causing grounding or short circuiting of the current, as frequently happens with timers or ordinary construction. The structural 70 assemblage also ensures a compact arrangement of the pivotally connected portions of the brackets and enclosure of the spring so that it will be protected to a maximum degree from damage or injury. The opening 19, the walls of which are beveled, is adapted to receive the periphery of the roller 26, when the latter is moved inwardly to a maximum extent, thus allowing retraction of the carrier arm to a minimum degree and 75 packing of the rotor in close compass for storage or shipment. The construction described is of further advantage in that sudden vibratory movements of the carrier arm and contact roller are prevented, thus obviating hammering or slamming of the roller on the surface of the raceway and the pitting thereof commonly caused in the use 80 of rotors of ordinary construction.

Having thus fully described my invention, I claim:

1. In a timer, a bracket for supporting a contact carrying bracket, said supporting bracket being unitarily formed from a stamping rolled to form a split sleeve, said sleeve having abutting edges, one of the abutting edges being formed with a pair of short arcuate side arms and an intervening recess arranged within the line of its circumference, and the other abutting edge having side abutment shoulders arranged within the line of its circumference and lying in abutting contact with said short arms, the latter named abutment edge also having a central arm extending tangentially beyond the circumference of the sleeve through said recess between said short arms and lying between the latter, the said central arm being bifurcated and having the bifurcation turned backwardly upon the outer face of said arm and formed to provide spaced hinge knuckles.

2. In a timer, a roller bracket carrying member comprising a pair of spaced, parallel longitudinal side plates having registering eyes at the opposite ends thereof, a bridge piece connecting the outer longitudinal edges of said plates, and a segmentally curved tongue extending from the bridge piece adjacent to and on a line between the eyes at one end of the bracket member and lying on an arc concentric with said eyes as a center.

In testimony whereof I affix my signature.
CHARLES KNAPP.
